(57) **CLAIM**

The ornamental design for a delivery syringe, as shown and described.

DESCRIPTION

FIG. 1 is a perspective view of a delivery syringe;
FIG. 2 is another perspective view of the delivery syringe;
FIG. 3 is a top view of the delivery syringe;
FIG. 4 is a bottom view of the delivery syringe;
FIG. 5 is a left-side view of the delivery syringe;
FIG. 6 is a right-side view of the delivery syringe;
FIG. 7 is a front view of the delivery syringe; and,
FIG. 8 is a rear view of the delivery syringe.
The broken lines in the drawings illustrate portions of the delivery syringe and form no part of the claimed design.
